[57] CLAIM

The ornamental design for a toaster oven, as shown and described.

DESCRIPTION

FIG. 1 is a perspective view as seen from the top, front and left side of a toaster oven showing our new design;

FIG. 2 is a front elevational view thereof;
FIG. 3 is a top plan view thereof;
FIG. 4 is a left side elevational view thereof;
FIG. 5 is right side elevational view thereof;
FIG. 6 is a rear elevational view thereof;
FIG. 7 is a bottom plan view thereof;
FIG. 8 is a perspective view as seen from the top, front and left side of a toaster oven showing a second embodiment thereof;
FIG. 9 is a front elevational view thereof;
FIG. 10 is a top plan view thereof;
FIG. 11 is a left side elevational view thereof;
FIG. 12 is a right side elevational view thereof;
FIG. 13 is a rear elevational view thereof;
FIG. 14 is a bottom plan view thereof;
FIG. 15 is a perspective view as seen from the top, front and left side of a control panel thereof;
FIG. 16 is a front elevational view thereof, the rear of the control panel not being seen in normal use;
FIG. 17 is left side elevational view thereof;
FIG. 18 is a right side elevational view thereof;
FIG. 19 is a top plan view thereof;
FIG. 20 is a bottom plan view thereof;
FIG. 21 is a perspective view as seen from the top, front and left side of a control panel thereof, with the control knobs removed for clarity of illustration;
FIG. 22 is a front elevational view thereof, the rear of the control panel not being seen in normal use;
FIG. 23 is left side elevational view thereof;
FIG. 24 is a right side elevational view thereof; and,
FIG. 25 is a top plan view thereof, the bottom plan view thereof being a mirror image.
The control panels in FIGS. 15-25 are shown separate for clarity of illustration, the claim being directed to the entire oven (embodiments 1 and 2) shown in FIGS. 1-14. The support feet shown in broken lines in FIGS. 1, 2, 4-6, 8-9, and 11-13 and the control knobs shown in broken lines in FIGS. 8-12, 14 and 21 are for illustrative purposes only and form no part of the claimed design.

1 Claim, 16 Drawing Sheets
